MULTIPLE-NECK FILTER

Walter van B. Roberts, Princeton, N. J., assignor
to Radio Corporation of America, a corporation
of Delaware

Original application March 30, 1949, Serial No.
84,372. Divided and this application July 8,
1950, Serial No. 172,746

8 Claims. (Cl. 333—71)

1

This application is a division of the copending application, Serial No. 84,372, filed March 30, 1949, now Patent No. 2,647,948, issued on August 4, 1953.

This invention relates to electromechanical filters. More particularly, it relates to bandpass filters (BPF's) of the mechanically-vibrating type.

As described in said application, several advantages are obtained through the use of mechanical resonators in filters for low radio frequencies. Such resonators are small, inexpensive and have very high Q's as compared to those of electrical circuits. According to said application, BPF's having extremely narrow pass-bands have been obtained by the use of mechanical resonator structures. Such structural arrangements generally consist of at least two like tuned mechanical resonator elements, aligned but spaced apart, with other elements positioned between and coupling together adjacent resonant elements. Such coupling elements have mechanical impedances different from that of the resonant elements or tanks. In effect, such coupling elements function to loosely couple together the tanks.

In a mechanical filter, the characteristic or mechanical impedance of each portion (tank and coupling portions) is the product of its cross sectional area and the intrinsic impedance of the material of which it is made, the latter quantity being in turn the product of its density and the velocity of propagation of longitudinal waves along that portion. If all the filter is made of the same material, the ratio p of the mechanical impedance of the coupling portion to that of the tank portions is simply the ratio of cross sections, assuming that the sections are small enough so that the compressional wave velocity is the same in all portions. Filters which have a value of p small compared to unity are known as "neck-type" or "neck-coupled" filters, and the present invention relates generally to filters of this type. In such filters, the coupling elements are of smaller transverse dimensions than the tank elements.

As disclosed in said application, for a BPF p must be of the order of the desired fractional bandwidth. The fractional bandwidth is defined as the ratio of the width of the filter pass-band in cycles per second to the mid frequency of the passband in cycles per second. If a one per cent band is required, this means that a neck-type filter turned out of round stock must have a neck diameter only about one-tenth that of the tanks. It may therefore be seen that narrowness of the

2

band is limited by flimsiness of the structure. Matters are even worse if the filter is cut out of flat strip material, because in this case the neck width must be p times the tank width.

5 In a neck-type filter, the tank elements are connected together by a neck so thin as to act at some frequencies like a weak spring. The smaller the cross section of the spring, the weaker is this spring and the more loosely the tank elements are coupled together. Also, the smaller the cross section of the spring or neck coupler, the smaller is the ratio p and the smaller is the fractional band-width. This is true since, as previously stated, p is of the order of the fractional bandwidth. Therefore, in general, the more loosely the tanks or resonators are coupled, the narrower is the width of the filter passband.

An object of this invention is to devise a mechanical BPF having a very narrow passband.

20 Another object is to disclose a simple and satisfactory method for obtaining a very narrow passband in an electromechanical BPF.

A further object is to disclose a method for obtaining very loose coupling between the resonant elements of a mechanical filter.

A still further object is to devise an arrangement permitting extremely loose coupling between tanks, in a neck-type filter, without requiring unduly small necks.

An additional object is to provide a neck-type mechanical BPF having a very narrow passband, without requiring unduly small necks.

The foregoing and other objects of the invention will be best understood from the following description of some examples thereof, reference being had to the accompanying drawing, wherein:

Fig. 1 is a somewhat schematic representation of a filter according to this invention; and

40 Fig. 2 is a partly diagrammatic representation of another filter according to this invention.

The objects of this invention are accomplished, briefly, in the following manner: Subsidiary filters, operating in an attenuating band, are used 45 as coupling elements between the tanks in a neck-coupled mechanical filter. Each of these subsidiary filters or coupling elements consists of at least two spaced neck coupling elements with intervening elements of larger cross section. Thus, multiple-neck coupling elements are utilized in the filter. The end neck elements of the subsidiary filters or low-pass filter (LPF) sections are connected to the tanks or resonators of the main filter. Thus, the entire arrangement 50 in effect consists of a composite filter, comprising

main filter resonators coupled by means of subsidiary filters.

Fig. 1 is a representation of a filter according to this invention. The filter is positioned between two permanent magnets 1 and 2 which establish magnetic flux longitudinally therethrough. The filter is metallic and may be either flat (being punched out of strip or sheet stock) or may be formed as figures of revolution, having circular cross section throughout. In Fig. 1, multiple-neck coupling elements are utilized. This figure shows a single-section neck-type filter coupled by twin elements. This filter consists of a pair of aligned half-wave resonant elements or tanks 3 and 4 coupled by twin quarter-wave necks 5 and 6 separated by a quarter-wave "slug" 7. The necks 5 and 6 are relatively thin compared to the tanks 3 and 4. The slug 7 is relatively thick compared to necks 5 and 6, so that it acts somewhat as a heavy mass. Both ends of each resonator 3 and 4 are motional loops at the frequency of operation.

Element 3 is the drive element or tank, while element 4 is the take-off tank. The filter 3-7 is mechanically driven by means of a coil 8 coupled to element 3, and take-off to an electrical circuit is by means of a coil 9 coupled to element 4. For magnetostrictive drive and take-off, the material used for the drive and take-off tanks must, of course, be magnetostrictive. For this purpose, nickel-plated aluminum may be used for the end tanks. This nickel plating makes possible magnetostrictive driving of, and take-off from, the tanks, in accordance with the principles disclosed in the copending Burns application, Serial No. 84,373, filed March 30, 1949, now Patent No. 2,619,604, issued November 25, 1952. Nickel has good magnetostrictive activity. The elements 5, 6 and 7 may be of this same magnetostrictive material or of suitable other metallic material, for example brass or nickel.

Driving coil 8 is coupled to the center portion of drive tank 3. Coil 8 is in effect wound around resonant element 3. Said coil is tuned by a condenser connected in parallel therewith and is connected to the output circuit of a driving amplifier tube 10. Tube 10 is supplied from a source of oscillatory energy, which source is of low radio frequency, for example, anywhere in the range of fifty to five hundred kilocycles, the upper limit being set chiefly by the decreasing dimensions of the parts. Coil 8 acting on tank 3 produces alternating longitudinal magnetization.

Take-off coil 9 is coupled to the center portion of take-off tank 4. Coil 9 is in effect wound around this resonant element. Said coil is tuned by a condenser connected in parallel therewith and is connected to the input circuit of an amplifier tube 11. Tube 11 may be termed a signal utilization means.

The polarizing magnets 1 and 2 apply a longitudinal magnetic field to tanks 3 and 4. Although two separate magnets are illustrated, it will be appreciated that a single horseshoe magnet could be used instead, if desired.

The combination of the constant longitudinal magnetization (produced by 1 and 2) and the alternating longitudinal magnetization produced by driving coil 8 results in longitudinal vibrations of resonator 3. This is due to magnetostrictive action.

The composite filter 3-7 is metallic and may be formed from a single piece of material. It can be either flat, in which case it is punched out of

strip or sheet stock, or round, in which case it is machined out of suitable round stock.

The coupling element 5-7 of Fig. 1 extends between tanks 3 and 4. This coupling element is of the multiple-neck type, being specifically of the twin-neck type. The coupling element itself consists of twin quarter-wave necks 5 and 6 separated by a quarter-wave slug 7. Elements 5, 7 and 6 are joined together end-to-end in that order. The remaining end of neck 5 is joined to tank 3 and the remaining end of neck 6 is joined to tank 4.

The multiple-neck coupling element 5-7 permits extremely loose coupling between tanks 3 and 4 without requiring an excessive ratio of the cross sections of tanks 3 and 4 to those of the necks. A physical picture of the operation of the coupling system 5-7 may be had by considering element 5 adjacent to tank 3 as the actual coupling element while the other two, 7 and 6, act as two quarter-wave transformers in tandem which transform the impedance of the other tank 4 to a value still further out of line with that of the coupling element 5. The impedance transformation, more specifically, is equal to the square of the ratio of the individual impedances. This results in a narrower band than that provided by a filter having a single-neck coupling, for the same ratio of impedances of the elements. For practical purposes, it is usually sufficient to figure that the filter's passband is narrower by the factor p as compared to the corresponding filter with a single neck coupling element.

Although the slug 7 is shown as having approximately the same transverse dimension as the tanks 3 and 4, this does not necessarily need to be the case. Slug 7 may have either a larger or smaller transverse dimension than do the tanks 3 and 4, as long as the mechanical impedance of said slug has the proper relation to that of necks 5 and 6. Making the slug 7 of the same transverse dimension or of the same impedance as tanks 3 and 4, facilitates analysis and is a convenient construction.

Another way of looking at the multiple coupler 5-7 is to consider it as a subsidiary filtering means or LPF operating above cut off. The coupler 5, 6, 7 can be considered a single section LPF. It therefore attenuates, in a nondissipative manner, vibrations passing through in either direction. Hence, it operates in an attenuating band at the frequency of operation of the filter section, which is determined by the frequency of the voltage applied to coil 8. This LPF connects or serves as the coupling between adjacent resonators 3 and 4. The subsidiary filter 5-7 attenuates as a result of mechanical impedance differences between certain of its elements and the remaining elements of the composite filter. From this point of view, it is evident that other forms of subsidiary filters, operating in an attenuating band, could be employed as loose coupling means between tanks of the composite filter 3-7. The composite filter can be said to consist of resonators 3 and 4 coupled by the subsidiary filter 5-7.

Since the subsidiary filter 5-7 operates in an attenuating band, it in effect provides very loose coupling between the tanks 3 and 4. This in turn results in a very narrow passband for the BPF 3-7.

The action at the end tank 4 is the converse of that described in connection with tank 3. Due to the constant longitudinal magnetization provided by magnets 1 and 2 and to the longitudinal motion of the magnetostrictively-active

material of tank 4, an alternating voltage is induced in coil 9 and fed to utilization means 11.

Another factor p may be obtained by adding another pair of quarter-wave elements to the coupling element of Fig. 1, to form a triple-neck coupling. In other words, the band may be narrowed still further by adding more pairs of large and small quarter-wave elements to the coupler. This will make the coupling between the tanks still looser, because it provides more attenuation in the filter-type coupling sections. Thus, by using a sufficient number of elements in the coupler it is possible to obtain as narrow a band as desired, without requiring p to be impractically small.

Fig. 2 illustrates a filter of the type just referred to. This figure shows a two-section (multiple-section) neck-type filter with triple-neck (multiple-neck) coupling. The drive end tank 12 and the take-off end tank 13 are each 10 half-wave resonators. Here, as in Fig. 1, all of the elements are aligned and connected in end-to-end relationship. End tank 12 is joined to a large central resonator 14 by a series of three quarter-wave neck elements 15, 16 and 17 and 15 two quarter-wave slug elements 18 and 19, the large and small (slug and neck) elements alternating between tank 12 and resonator 14. One end of end neck 15 of the coupling element 15-19 is joined to tank 12. One end of the opposite 20 end neck 17 of coupler 15-19 is joined to central resonator 14. Resonator 14 is a one-wavelength resonator.

The three necks 15, 16 and 17, in conjunction with slugs 18 and 19, form a triple-neck coupling between tank 12 and resonator 14. Multiple-neck coupler 15-19 provides a subsidiary filter, operating in an attenuating band, to serve as loose coupling means between resonators 12 and 14. The triple-neck coupler of Fig. 2 provides a narrower filter passband than does the twin-neck coupler of Fig. 1. The coupling element 15-19 can be considered a two-section LPF.

Similarly, end tank 13 is joined to resonator 14 by a series of three quarter-wave neck elements 20, 21 and 22 and two quarter-wave slug elements 23 and 24, the slug and neck elements alternating between tank 13 and resonator 14. One end of end neck 20 of coupling element 20-24 is joined to tank 13. One end of the opposite end neck 22 of coupler 20-24 is joined to central resonator 14. The three necks 20, 21 and 22, in conjunction with slugs 23 and 24, form a triple-neck coupling between tank 13 and resonator 14. The multiple-neck coupler 20-24 likewise provides a subsidiary filter, operating in an attenuating band, to serve as loose coupling means between resonators 13 and 14. The coupler 20-24 can be considered a two-section LPF.

As in Fig. 1, end tanks 12 and 13 are magnetized longitudinally by permanent magnets 1 and 2 and are located in drive and take-off coils 8 and 9, respectively. Longitudinal vibrations 65 occur due to magnetostriuctive action.

The Fig. 2 arrangement is a two-section composite filter in that each half of the structure, that is, one end tank, half the central resonator, and the quarter-wave elements between them, is a single-section filter. The two sections of this filter are placed end-to-end. In this connection, it is desired to be pointed out that, if desired, two or more single-section composite filters of the Fig. 1 type could be joined end-

to-end to provide a multi-section, twin-neck-coupled filter. Such joining together end-to-end of the plurality of sections could be effected in accordance with the arrangement illustrated in Fig. 2.

Fig. 2 shows, for example, a two-section filter made of sheet nickel that has, in the design illustrated, one passband from 94.7 to 97 kilocycles and another from 276 to 279.5 kilocycles. In this particular design, the end tanks 12 and 13 were each one inch long. The central element 14 was two inches long, elements 15-24 each being $\frac{1}{2}$ -inch long. The ratio of widths of the wide and narrow elements was 3:1. The overall length of this filter, excluding permanent magnets, was nine inches.

Also, if desired, the coupling element of the single-section Fig. 1 filter could be modified in accordance with the teaching of Fig. 2 to provide a single-section, triple-neck-coupled filter.

Although the filter of Fig. 2 is illustrated as having only two sections, it is desired to be pointed out that the concept of Fig. 2 may be extended by the joining on of additional sections in end-to-end relationship, to provide a filter of more than two sections.

What I claim to be my invention is as follows:

1. A mechanical filter section, comprising a pair of spaced resonant elements and coupling means therebetween, said means consisting of a coupling element having a plurality of portions of different mechanical impedances, the length of each of said plurality of portions being substantially a quarter-wavelength at the frequency of operation of said filter section.

2. A mechanical filter section, comprising a pair of spaced resonant elements and coupling means therebetween, said means consisting of a multipartite coupling element having two portions of a certain mechanical impedance and at least one portion positioned therebetween of a different mechanical impedance, said two portions being joined one to each of said resonant elements, the length of each portion of said multipartite coupling element being substantially a quarter-wavelength at the frequency of operation of said filter section.

3. A mechanical filter section, comprising a pair of spaced resonant elements and multipartite coupling means therebetween, said means consisting of two portions of a certain mechanical impedance and one portion, of a higher mechanical impedance, positioned between said two portions and joining the same together, said two portions being joined at their free ends one to each of said resonant elements, the length of each portion of said multipartite coupling means being substantially a quarter-wavelength at the frequency of operation of said filter section.

4. A mechanical filter section, comprising a pair of spaced resonant elements and coupling means therebetween, said means consisting of a multiple coupling element which includes two spaced segments having a certain mechanical impedance, two spaced segments of a higher mechanical impedance, and one other segment of a mechanical impedance less than said higher impedance, said one segment being positioned between and joining together said two segments of higher impedance, said one segment and said two segments of higher impedance being positioned between and joining together said two segments of certain impedance, and said two segments of certain impedance being joined at their free ends one to each of said resonant elements, the length of each segment

of said multiple coupling element being substantially a quarter-wavelength at the frequency of operation of said filter section.

5. A multisection mechanical filter, comprising a plurality of identical sections connected in end-to-end relationship, each of said sections consisting of a pair of spaced resonant elements joined by coupling means, each coupling means consisting of a multiportion coupling element having two portions of a certain mechanical impedance and at least one portion positioned therebetween of a different mechanical impedance, said two portions being joined one to each of said resonant elements, the length of each portion of said coupling element being substantially a quarter-wavelength at the frequency of operation of said filter.

6. A multisection mechanical filter, comprising a plurality of identical sections connected in end-to-end relationship, each of said sections consisting of a pair of spaced resonant elements joined by coupling means, each coupling means consisting of a coupling element having two portions of a certain mechanical impedance and at least one portion positioned therebetween of a higher mechanical impedance, said two portions being joined one to each of said resonant elements, the length of each portion of said coupling element being substantially a quarter-wavelength at the frequency of operation of said filter.

7. A mechanical filter providing a band-pass characteristic, comprising a pair of spaced resonant elements tuned to a frequency within said pass band, and coupling means therebetween,

said coupling means comprising, in the order named, a neck element of lesser dimension than the resonant elements, a slug element of larger dimension than said neck element, and a second neck element to constitute at least one low pass mechanical filter section which operates in an attenuation band at the frequency of operation of said filter.

8. A mechanical filter providing a band-pass characteristic comprising, in the order named, a first resonator element, a first coupling neck, a first coupling slug, a second coupling neck, a second coupling slug, a third coupling neck, and a second resonator element, said first and second resonator elements being tuned to resonate at a frequency within the pass band of the filter, said coupling necks having smaller cross-sectional dimension than said slugs, said coupling necks and slugs constituting a subsidiary filter having an attenuation band at the band pass frequency of the filter.
